UNITED STATES PATENT OFFICE.

WILLIAM H. MAGEE, OF MOUNDSVILLE, WEST VIRGINIA, ASSIGNOR TO FOSTORIA GLASS CO., OF MOUNDSVILLE, WEST VIRGINIA, A CORPORATION OF WEST VIRGINIA.

DESIGN FOR A VASE.

Application filed December 28, 1925. Serial No. 15,884. Term of patent 14 years.

To all whom it may concern:

Be it known that I, WILLIAM H. MAGEE, a citizen of the United States, residing at Moundsville, in the county of Marshall and State of West Virginia, have invented a new, original, and ornamental Design for Vase, of which the following is a specification, reference being had to the accompanying drawing, forming part thereof.

The figure is a perspective view of the vase showing my new design.

I claim:

The ornamental design for a vase, as shown.

WILLIAM H. MAGEE.
